UNITED STATES PATENT OFFICE.

WILLIAM H. C. HIGGINS, JR., OF LAPORTE, INDIANA, ASSIGNOR TO M. RUMELY COMPANY, OF LAPORTE, INDIANA, A CORPORATION OF INDIANA.

VALVE.

1,060,089.

Specification of Letters Patent. Patented Apr. 29, 1913.

Application filed October 31, 1912. Serial No. 728,799.

To all whom it may concern:

Be it known that I, WILLIAM H. C. HIGGINS, Jr., a citizen of the United States, residing at Laporte, in the county of Laporte 5 and State of Indiana, have invented a certain new and useful Improvement in Valves, of which the following is a specification.

My invention relates to improvements in carburetor valves and is illustrated in the 10 accompanying drawing, which is a vertical cross-section through a valve adapted to be used to introduce fuel or water into the mixing or carbureting chamber.

It will be understood that the liquid 15 chamber is embraced between the upper wall A and the lower wall A¹ and that the carbureting or mixing chamber lies below the wall A¹. The valve consists of the cylinder B screw-threaded at B¹, perforated 20 at B² and adapted to rest at B³ on the lower wall A¹. It is surrounded by the gauze cylinder B⁴. Within the cylinder B is the cylinder C screw-threaded at C¹, perforated above at C², provided with a long 25 hanging nozzle portion C³ which carries a washer C⁴ whereby a tight joint is made between the upper part of the nozzle C³ and the lower part of the wall A¹. The cylinder B is also internally screw-threaded 30 at C⁵ to engage the stem D, screw-threaded at D¹ and provided with the hand wheel D². The spring D³ is placed between the wheel D² and the upper wall A. On the lower end of the stem is the valve D⁴ with 35 the guide flange D⁵ partly encircling the stem above the valve and a valve seat D⁶ in opposition to the valve.

The inner cylinder is held in position on the outer cylinder because of their screw- 40 threaded engagement and both are rigidly and firmly clamped to the lower wall A¹ so as to make a tight joint therewith on the lower side. The valve stem is screwed into the inner cylinder and the valve can be set 45 at any desired position by operating the hand wheel in opposition to the spiral spring.

The fluid be it water or liquid fuel contained in the chamber between the walls A 50 and A¹ is first strained through the gauze cylinder. It then enters the perforations B², passes upwardly through the two cylinders, passes through the perforations C² in the inner cylinder and down about the 55 stem and out between the valve and valve

seat through or along the walls of the nozzle. In practice the level of fluid in the chamber is maintained at about the height of the perforation C², and as long as a vacuum is created in the mixing chamber below the wall A¹ the fluid is raised to the level of the aperture C², whereupon it flows downwardly and out through the nozzle. 60

I claim:

1. A fuel supply valve for carburetors comprising a cylinder having a wall perforate near its upper end, a valve and valve seat near its lower end and a jacket surrounding it, a chamber formed within the jacket and surrounding the cylinder, said 65 jacket having a wall perforate toward its lower end.

2. A fuel supply valve for carburetors comprising a cylinder having a wall perforate near its upper end, a valve and valve 70 seat near its lower end and a jacket surrounding it, a chamber formed within the jacket and surrounding the cylinder, said jacket having a wall perforate toward the lower end, said cylinder having a downwardly opening conical discharge nozzle. 75

3. A fuel supply valve for carburetors comprising a cylinder having a wall perforate near its upper end, a valve and valve 80 seat near its lower end and a jacket surrounding it, a chamber formed within the jacket and surrounding the cylinder, said jacket having a wall perforate toward the lower end, said cylinder having a downwardly opening conical discharge nozzle, 85

3. A fuel supply valve for carburetors comprising a cylinder having a wall perforate near its upper end, a valve and valve 90 seat near its lower end and a jacket surrounding it, a chamber formed within the jacket and surrounding the cylinder, said jacket having a wall perforate toward the lower end, said cylinder having a downwardly opening conical discharge nozzle, 95

4. A fuel supply valve for carburetors comprising a cylinder having a wall perforate near its upper end, a valve and valve 100 seat near its lower end and a jacket surrounding it, a chamber formed within the jacket and surrounding the cylinder, said jacket having a wall perforate toward the lower end, said cylinder having a downwardly opening conical discharge nozzle, the valve seat in said cylinder being located at the apex of the nozzle, said valve being carried by a valve stem screw threaded in the top of the cylinder. 105

5. A fuel supply valve for carburetors comprising a cylinder having a wall perforate near its upper end, a conical discharge nozzle at its lower end, a valve seat 110 at the apex of the nozzle, a valve stem screw-

threaded in its upper end, and a needle valve carried by the valve stem and in opposition to the valve seat, a cylindrical jacket surrounding the cylinder having a wall perforate at the bottom, a space between the cylinder and the jacket and a screen surrounding the perforated part of the jacket wall.

6. A fuel supply valve for carbureters comprising a cylinder having a wall perforate near its upper end, a conical discharge nozzle at its lower end, a valve seat at the apex of the nozzle, a valve stem screw threaded in the upper end of the cylinder, and a needle valve carried by the valve stem and in opposition to the valve seat, a cylindrical jacket surrounding the cylinder having a wall perforate at the bottom, a space between the cylinder and the jacket.

7. A needle valve for carbureters comprising an outer perforate sleeve, a screen surrounding the base of said sleeve and in opposition to the perforations therethrough, an inner perforate sleeve screw threaded in said outer sleeve and terminating at its bottom in a bell mouthed discharge nozzle, the perforations in said inner sleeve being located adjacent its top, an annular conical valve seat within said sleeve and a needle valve in opposition to said seat.

8. A needle valve for carbureters comprising an outer perforate sleeve, a screen

prising an outer perforate sleeve, a screen surrounding the base of said sleeve and in opposition to the perforations therethrough, an inner perforate sleeve screw threaded in said outer sleeve and terminating at its bottom in a bell mouthed discharge nozzle, the perforations in said inner sleeve being located adjacent its top, an annular conical valve seat within said sleeve and a needle valve in opposition to said seat.

9. A needle valve for carbureters comprising an outer perforate sleeve, a screen surrounding the base of said sleeve and in opposition to the perforations therethrough, an inner perforate sleeve screw threaded in said outer sleeve and terminating at its bottom in a bell mouthed discharge nozzle, the perforations in said inner sleeve being located adjacent its top, an annular conical valve seat within said sleeve and a needle valve in opposition to said seat, a guide collar upon said needle valve engaging the walls of said sleeve and slots through said collar.

In testimony whereof, I affix my signature in the presence of two witnesses this 28th day of October 1912.

WILLIAM H. C. HIGGINS, JR.
